UNITED STATES PATENT OFFICE.

JOHN A. ZERWER, OF ALMA, TEXAS.

TIE-UP STAND FOR MAIL.

1,229,006.

Specification of Letters Patent. Patented June 5, 1917.

Application filed July 12, 1916. Serial No. 108,810.

To all whom it may concern:

Be it known that I, JOHN A. ZERWER, a citizen of the United States, residing at Alma, in the county of Ellis, State of Texas, have invented certain new and useful Improvements in Tie-Up Stands for Mail; and I do hereby declare the following to be a full, clear, and exact description of the invention, such as will enable others skilled in the art to which it appertains to make and use the same.

This invention relates to a tie-up stand for mail.

An object of the invention resides in the provision of a device of this character by means of which the mail may be held in stacks during the tying up or the placing of a strap about the same.

A further object of the invention resides in the provision of a device which is adjustable so that it will accommodate pieces of mail of various widths.

A still further object of the invention resides in the provision of a device which may be cheaply manufactured, easily assembled and conveniently used.

With these and other objects in view, such as will appear as my description progresses, my invention comprises the combination and arrangement of parts as set forth in and falling within the scope of the appended claims.

In the drawing:

Fig. 1 is a plan view of a device constructed in accordance with my invention;

Fig. 2 is an elevational view of the same;

Fig. 3 is a similar view looking at right angles to Fig. 2;

Fig. 4 is a transverse sectional view showing the clamping means for the slide;

Fig. 5 is a longitudinal sectional view, and

Fig. 6 is a detail of the blank used in forming the base.

The embodiment of my invention illustrated in the drawing includes a base which comprises a lower plate 1 and an upper plate 2 which are held in spaced relation, at their ends, by cross bars 3. These plates 1 and 2 are made integral with each other, being formed from a single sheet of metal bent back upon itself. The upper plate 2 is provided, adjacent each of its edges, with a slot 4, which slots extend longitudinally of the base and terminate short of the ends thereof. A comparatively wider slot 5 is formed in

the plate 2 between the slots 4 and is co-extensive therewith. Secured to the bar 3 at one end of the base and extending upwardly therefrom is a pair of inverted U-shaped guides 6 which act to secure the plates 1 and 2 to the bar 3 and between which a space 7 is formed. Slidably mounted between the plates 1 and 2 is a plate 8 to which a pair of U-shaped guide members 9 are secured, which members extend upwardly through the slots 4 and 5 and between which a space 10 is formed, which space is in alignment with the space 7 between the member 6. The movement of this plate 8 is limited in one direction by the bar 3 at one end of the base and in the other direction by the contacting of the guides 9 with the ends of the slots 4 and 5.

In order that this plate 8, together with the guide members which it carries, may be secured in various and predetermined positions, I have provided the same with an upwardly extending screw 11 which projects through the slot 5 in the plate 2 and which projects through a plate 12 which is slidably mounted on the upper face of the plate 2 and extends completely thereacross. The under face of this plate 12 is provided with channels 13 which ride upon the edges 14 of the plate 2, which edges are slightly raised above the plane of the plate. A thumb nut 15 is mounted on the screw 11 and when tightened is adapted to force the plate 12 tightly against the plate 8 so as to bind the latter in position.

In using the device the plate 8 is adjusted so that the guides 6 and 9 are located the proper distances apart and the nut 15 is tightened so that the guides will be secured in these positions. A tie strap is placed longitudinally of the base so that it extends through the spaces 7 and 10 and rests upon the base. The package of mail is then placed upon the strap between the guides 6 and 9 and the strap fastened about the bundle which may then be removed.

Thus it will be seen that I have provided a device in which the base is made of a single sheet of metal and which is so constructed that bundles of mail of various sizes may be formed.

While I have illustrated and described a particular embodiment of my invention, it has merely been for the sake of convenience and I do not wish to be limited to that particular embodiment as it is obvious that

numerous changes may be made in the details of construction without departing from the spirit of the invention or exceeding the scope of the appended claims.

5. What I claim is:—

1. In a device of the class described, the combination with a base including a pair of vertically spaced plates formed from a single sheet of metal, of a pair of spaced guides extending upwardly from one end thereof, a plate mounted between the first mentioned pair of plates, spaced guides carried by said last mentioned plate, and means for arresting the movement of the guides in each direction.
15. 2. In a device of the class described, the

combination with a base including a pair of spaced plates having longitudinally extending parallel slots therein, guides secured to and extending upwardly from the base, an 20 adjustable plate mounted between the pair of plates, guides secured to the adjustable plate and extending upwardly through the aforementioned slots and means carried by the last mentioned plate for securing it in 25 position.

In testimony whereof, I affix my signature, in the presence of two witnesses.

JOHN A. ZERWER.

Witnesses:

G. W. CALLORD,
J. L. CAYCE.
